UNITED STATES PATENT OFFICE.

CARL A. BJORNSSON, OF WELLSVILLE, NEW YORK, ASSIGNOR TO McEWEN BROS., OF WELLSVILLE, NEW YORK, A CORPORATION OF NEW YORK.

INTERNAL-COMBUSTION ENGINE.

Application filed July 18, 1924. Serial No. 726,663.

To all whom it may concern:

Be it known that I, CARL A. BJORNSSON, a citizen of the United States, residing at Wellsville, in the county of Allegany and 5 State of New York, have invented certain new and useful Improvements in Internal-Combustion Engines, of which the following is a specification.

This invention relates to internal combustion engines of the oil or Diesel type and, 10 more particularly, to a fuel injecting and control apparatus for engines of this type.

In the usual type of four cycle, internal combustion, engines of this type, the engine pistons make two complete reciprocations, and the crank shaft two revolutions, for each explosion and accordingly for each injection of fuel. The fuel injecting pump must, therefore, be operated at alternate 15 revolutions of the crank shaft and this has usually been done by driving the pump from the cam shaft or other shaft rotating at one half the speed of the crank shaft. As the fuel pump must supply the fuel at a high 20 pressure, the driving of the fuel pump from the cam shaft has imposed a heavy stress on this shaft and its driving gears and has necessitated the use of a more massive shaft and driving mechanism than would otherwise be required.

An object of my present invention is to provide a fuel injecting mechanism for four cycle internal combustion engines which may be driven directly from the crank shaft 25 of the engine.

Another object of the invention is to provide a mechanism for controlling the quantity of fuel injected at each stroke of the pump which will require a minimum of 30 force or pressure from the governing mechanism and which will provide a sensitive and responsive operation of the fuel control.

Further objects of the invention are to provide a means for driving a fuel injecting pump from the crank shaft of an engine in which the driving mechanism is moved 35 out of driving position at alternate rotations of the shaft and in which the injection of fuel may be made rapidly in a very short 40 period of time, and to provide a controlling fuel by-pass mechanism which will relieve or equalize the fluid pressure on the valve 45 immediately prior to its opening.

With these and other objects in view,

which will appear from the following description, the invention comprises the engine and mechanism described and set forth in the following specification and claims.

The various features of the invention are illustrated in the accompanying drawings, 60 in which:

Fig. 1 is a vertical sectional view through a portion of an engine and fuel injecting means embodying a preferred form of the invention, the section being taken on approximately the center line of the engine crank shaft,

Fig. 2 is a vertical section of a portion of the engine and fuel injecting means taken on line 2—2 of Fig. 1, and,

Fig. 3 is an enlarged, sectional, view of the fuel injecting and regulating mechanism shown in Fig. 2.

In my present invention, the fuel injecting pump or piston is driven directly from the engine crank shaft by a driving connection, which reciprocates with each revolution of the crank shaft, and the feeding stroke of which is rendered inactive for its respective cylinder at each alternate reciprocation, 75 preferably by being moved out of engagement with the pump piston, so that the pump is given a feeding thrust at alternate revolutions, or once for each four cycles. A constant quantity of fuel is drawn into the fuel 80 feeding pump on each suction stroke and the quantity of fuel supplied to the engine is controlled by by-passing a portion of this fuel through the inlet valve, which is for 85 this purpose opened at a suitable portion of the feeding stroke, the time of opening of this valve being controlled by a governor or regulator.

The controlling mechanism comprises a floating lever, one end of which is raised and lowered by the piston driving 90 means while the other end is fulcrumed on a control element which may be raised and lowered to control the position of the lever and thus the point at which the fuel is bypassed. To reduce the force required to lift 95 the inlet valve against the fluid pressure in the pump, a small by-pass valve is provided to open immediately prior to the opening of the inlet valve and to thus equalize the pressures on opposite sides of this valve at the 100 time of opening.

Referring more particularly to the accompanying drawings, the invention is illustrat-

ed as applied to an engine having a number of fuel supply pumps 10 and 11, two being shown by way of example, arranged to supply a corresponding number of engine cylinders, and mounted in a housing 12 which also encloses the engine crank shaft 13. As the pumps 10 and 11 are substantial duplicates, but one will be described, it being understood that the description applies 10 equally to both pumps.

The piston of each pump is driven from the crank shaft 13 by means of an eccentric 14 keyed, or otherwise rigidly secured, on the shaft and surrounded by a suitable eccentric strap 15. The reciprocations of the strap 15 are transmitted through a roller 16 mounted on a pin 17 in a bracket 18 on the upper side of the strap 15 and adapted to strike and lift a stem 19 depending from a 20 piston 20 in a cylinder 21 of the pump 10 or 11 when in alignment therewith. The stem 19 and piston 20 are returned to their lowermost position by any suitable means, as for example, by means of a spring 22 confined 25 between the under face of the pump and a collar 23 mounted on the stem 19, and the downward movement of the stem and piston is limited by means of a shoulder 24 on the lower portion of the stem positioned to stop 30 against a guide collar 25 on an inner wall of the crank casing 12.

Through the above described mechanism, if the roller 16 were kept in alignment with the piston stem 19 and the crank shaft axis, 35 the eccentric 14 would give the piston a thrust at each revolution of the crank shaft and would thus feed fuel at every two cycles instead of at each four cycles as desired. To render the fuel feed inactive at alternate rotations of the crank shaft, the roller 16 is 40 swung clear of the piston stem at every other stroke by means of an eccentric 26 on a shaft 27 rotated at cam shaft speed, or at one half the speed of the crank shaft, and connected 45 to the roller 16 by means of a rod 28 having at one end an eccentric strap 29 embracing the eccentric 26 and, at its other end 30, forked and secured to the pin 17. The angular position of the shaft 27 is such, relative to the shaft 13, that during an upper 50 stroke of the eccentric strap 15 and roller 16, the roller is held in alignment with the piston stem 19 and crank shaft axis as indicated in full lines in Fig. 2. Upon a complete revolution of the crank shaft and subsequent upward stroke of the roller 16, the 55 shaft 27 will have completed a half revolution, bringing the roller into the position indicated in broken lines in Fig. 2 and thus 60 into a position in which the roller just clears the end of the piston stem. The pump piston is therefore driven upwardly, forcing a charge of fuel to the cylinder and returning and drawing in a new charge on one revolution 65 of the crank shaft and remains inactive

on the next succeeding revolution and upon the third revolution, again driving the charge of fuel to the engine cylinder and drawing in a fresh charge.

It is to be noted that the forcing and suction movements of the piston are much shorter and more rapid than would be the case if the driving eccentric were rotating at cam shaft speed, thus enabling the injection of the fuel to take place in a shorter period 75 of time and to be more closely and accurately timed. As the crank shaft must be of massive construction to receive the thrusts of the engine pistons, it is well adapted for driving the fuel feed pumps and inasmuch as the 80 guiding or cam shaft has merely to tilt the driving eccentric strap, it may be made of light construction and imposes no considerable stress on its driving gears.

The shaft 27 may be driven at cam shaft 85 speed by any suitable or standard means as indicated diagrammatically in Fig. 1, for example. In this case, the shaft 27 is driven from the crank shaft through a gear 31 fixed 90 on the crank shaft and meshing with an idler spur gear 32 mounted on a shaft 33 on which is also mounted a gear 34 which in turn meshes with and drives a spur gear 35 rigidly mounted on the shaft 27. The diameters of the gears 31, 32, 34, and 35 are such 95 as to reduce the speed of the shaft 27 to one half that of the crank shaft as, for example, by making the gear 32 of twice the diameter of the gear 31 and making the gears 34 and 35 of equal diameters.

Upon each downward stroke of the pump piston 20 a charge of fuel is drawn from a source of supply through an inlet pipe 36 and a passage 37 to a valve chamber 38 lifting an inlet check valve 39 therein, and thence passing through a passage 40 to the pump cylinder 21 to fill the cylinder with a charge of fuel.

As the piston 20 is again forced upwardly, 110 the charge of fuel is forced backwardly through the passage 40, closing the inlet check valve 39 on its seat, and thence passing upwardly through the valve chamber 38, lifting an outlet valve 41 therein and passing through an outlet passage 42 leading to the combustion chamber of the engine cylinder. Upon each stroke of the pump piston, therefore, a fixed, constant, quantity of fuel is drawn into the pump cylinder and forced out, this quantity being sufficient to drive the 115 engine at maximum load.

When the engine is running at less than full load, a portion of the charge of fuel is by-passed, on the delivery stroke, to the inlet passage 37 and permitted to return to the source of supply or to be again drawn into the pump cylinder with the next charge. To this end, a lever 43 for actuating the by-passing of the fuel is fulcrumed 125 at one end on a vertically adjustable, hori- 130

zontal, supporting rod 44 and pivotally attached at its other end to the piston stem 19 in such a manner as to be tilted upwardly and downwardly on the rod 44 by the movement of the stem 19. A vertical valve actuating rod 46 is mounted on the lever 43 between the fulcrum rod 44 and the piston stem 19 and extends upwardly into the valve chamber 38 to a sufficient distance to reach 10 and lift the valve 39 when the lever 43 is lifted to a sufficiently high position by the fulcrum 44 and piston stem 19. The rod 46 and lever 43 are normally held downwardly on their supports by means of a 15 spring 47 confined between a flange 48 on the rod 46 and the under face of the valve chamber structure.

As the valve 39 is held downwardly on its seat by the full fluid pressure of the fuel 20 in the outlet passages acting on the entire surface of the valve, considerable force would be required to lift this valve against this fluid pressure. To diminish the force required to lift the inlet valve, the valve 39 25 is provided with a small, pressure release valve 49 seating on, and closing, a by-pass passage 50 in the valve 39, on which it is resiliently held by a spring 51 as well as by the fluid pressure in the valve chamber, 30 which is much less than that exerted on the valve 39 because of the smaller area of the valve 49. The by-pass mechanism for the valves 39 and 49 is therefore so arranged as to lift the valve 49 and open the small 35 by-pass passage 50 immediately prior to the lifting of the valve 39, thus releasing the pressure on the larger valve in time to enable it to be easily lifted.

For this purpose, the valve 39 is provided with a hollow, downwardly depending, guide stem 52 having suitable guide vanes, and the valve 49 is provided with a downwardly depending stem 53, within the stem 52 and projecting to a distance slightly below the bottom of the stem 52 when the valve 49 is seated on the valve 39. Accordingly, when the rod 46 is brought upwardly against the stems 52 and 53, it lifts the stem 52 and valve 49 and immediately thereafter 50 reaches and lifts the stem 53 and permits the fuel to escape to the inlet pipe 36.

The point in the vertical movement of the piston 20 at which the rod 46 opens the valve 39 is governed by the vertical position of the horizontal fulcrum rod 44, which is so mounted eccentrically on a rotatable journal 54 that, as the journal rotates the rod 44 is lifted or lowered. The position of the journal 54 and rod 44 may be controlled 55 by a lever 55 connected by a link 56 to a suitable control or governor. When the rod 44 is in its lowermost position, the lever 43 is fulcrumed so low that the rod 46 does not reach the stems 52 and 53 even when the 60 piston 20 reaches its upper limit of move- 65

ment and the full quantity of fuel is delivered to the engine cylinder, while, when the rod 44 is in its uppermost position, the inlet valve 39 is opened very early in the stroke of the piston 20, thus delivering a 70 minimum of fuel to the engine cylinders.

To enable the position of the governing lever 43 to be adjusted relative to its supporting and actuating elements, it is not mounted directly on the fulcrum rod 44 but 75 is provided with a vertically adjustable stem 57 threaded in the end of the lever and having a supporting surface 58 on its lower end. The upper end of the stem 57 is squared as at 59 to enable it to be turned by a wrench 80 and a lock nut 60 is provided to lock the stem 57 in position. With this arrangement, the control of the fuel feed may be readily adjusted.

The pump structure may be placed in any 85 suitable, convenient position on the engine. It is preferably formed in a block mounted on the upper wall of the crank casing, which is provided with an opening 62 through which the lower face of the block is open 90 to the crank case and driving mechanism. The pump cylinder is formed by a suitable hole or bore in the cylinder block and a casing 63 held therein by means of a threaded retaining gland 64, which also serves as a 95 supporting stop for the upper end of the spring 22. A sleeve 65 for the portion of the rod 46 extending into the valve chamber 38 is similarly mounted and retained in the pump block by means of a retaining 100 gland 66.

As changes of construction could be made within the scope of my invention, it is desired that all matter contained in the above 105 description or shown in the accompanying drawings shall be interpreted as illustrative and not in a limiting sense.

Having described my invention, what I claim and desire to secure by Letters Patent is:

1. An internal combustion engine which comprises, a crank shaft and a cylinder, a pump for forcing fuel from a supply source to said cylinder, said pump having means for transmitting a thrust from said crank shaft direct to fuel to be forced to said cylinder, and means causing said pump to supply fuel to said cylinder only on alternate revolutions of said crank shaft.

2. An internal combustion engine comprising a crank shaft, a fuel injecting piston, a reciprocating member driven from said crank shaft, and means for transmitting alternate thrusts of said reciprocating member to said piston.

3. An internal combustion engine comprising a crank shaft, a fuel injecting piston, an eccentric on said crank shaft, an eccentric strap on said eccentric, a reciprocating member driven from said strap, and means for

swinging said reciprocating member out of alignment with said piston at alternate revolutions of said crank shaft.

4. An internal combustion engine which 5 comprises a crank shaft, a cylinder, a fuel pump for forcing fuel from a supply source to said cylinder, said pump having means for transmitting a thrust from said crank shaft direct to fuel to be forced to said cylinder, and means rendering said thrust transmitting means inactive on alternate revolutions of said crank shaft.

5. An internal combustion engine which 10 comprises a crank shaft, a fuel injecting means comprising a piston, means driven from said crank shaft for reciprocating said piston, a shaft, means for driving said shaft at one half the speed of said crank shaft, and means actuated from said shaft to withdraw 15 said reciprocating means from engagement with said piston at each revolution of said shaft.

6. An internal combustion engine which 20 comprises a crank shaft, a fuel injecting means comprising a piston, a reciprocating member driven by said crank shaft and adapted to reciprocate in alignment with said piston, a shaft, means for driving said shaft at one half the speed of said crank 25 shaft, an eccentric on said shaft, and means connecting said eccentric to said reciprocating member to place said member into and out of alignment with said piston.

7. An internal combustion engine which 30 comprises a crank shaft, a fuel injecting

means comprising a piston, an eccentric on said crank shaft, an eccentric strap encircling said eccentric, a roller mounted on said eccentric strap, and means for moving said roller into position to actuate said piston on alternate revolutions of said crank shaft. 40

8. An internal combustion engine which 45 comprises a crank shaft, a fuel injecting means comprising a piston and a stem depending from said piston, an eccentric on said crank shaft, an eccentric strap encircling said eccentric, a roller mounted on said eccentric strap, means for moving said roller into position to strike and move the piston stem on alternate revolutions of said 50 crank shaft, and a spring for returning said piston and stem on the return movement of said roller.

9. An internal combustion engine which 55 comprises a crank shaft, a fuel feeding means comprising a piston driven by a direct thrust from said crank shaft and an inlet valve, means for rendering said piston driving means inactive on alternate rotations of said crank shaft, means for opening said inlet valve during the delivery stroke of said piston, a by-pass valve for said inlet, means for opening said by-pass valve immediately prior to the opening of said inlet valve, and means for adjusting the 60 portion of said delivery stroke of said piston during which said inlet valve is open. 65

In testimony whereof I affix my signature.

CARL A. BJORNSSON.
